PILE FABRIC

William E. Clarke, Worcester, Mass., assignor to
 M. J. Whittall Associates, Inc., Worcester,
 Mass., a corporation of Massachusetts

Application April 23, 1940, Serial No. 331,115

2 Claims. (Cl. 139—401)

This invention relates to woven pile fabrics, and especially such as are used in the manufacture of rugs and carpets in which a design is outlined by omitting tufts of the pile fabric to create such designs, and which may be produced on standard looms by proper control of the operations.

Various methods have been employed for producing carpets the designs in which have an embossed or bas-relief effect, and the working of designs in carpets by floating the pile warp yarns between certain of the weft shots and raising the pile warp to form tufts between other of the weft shots is well known in the art.

In the construction of carpets and rugs containing designs so outlined it is obvious that those raised tufts forming the boundaries of the design are less resistant to the weight imposed upon them than are those tufts which are supported by each other in the body of the fabric, and while it is the intention that the tufts along the boundaries should, to some extent, splay and cover the unraised warp it is desirable that they not be so crushed that the unraised pile area forming the outline of the design will, in effect, become wider and objectionable in appearance.

My invention aims to provide a means whereby the boundaries of the design outlined in the manner indicated are enhanced in appearance, and so arranged that they will offer greater resistance to the weight put upon them, and which will enable such boundaries to retain their original appearance much longer than heretofore.

In the drawing—

Figure 1 is a perspective view of a carpet or rug embodying my invention, the rows of tufts being shown extended to show more clearly the arrangement of staggered end tufts.

Figure 2 is a plan view of a carpet showing figure and ground areas constructed according to my invention.

For purposes of illustration I have shown in Fig. 1 a carpet constructed of two pile warps 3 and 4, stuffer warps 5, upper weft shots 6 and lower weft shots 7, binder warps 8 and 9 which cross the weft shots above and below, holding the weft shots in place against the stuffer warps. In weaving the fabric the pile warp yarns are raised over pile wires in the usual way to form loops extending upward between adjacent upper weft shots 6, and upon withdrawal of the wires the loops are cut at the top to produce the tufts 11.

For the production of a fabric according to my

invention I use a Wilton loom of the usual type, a jacquard mechanism controlling the manipulation of the pile warp yarns 3 and 4. In the construction of the fabric I employ three harness frames, two of which are filled with pile yarns, and a yarn from each of the two harness frames is drawn through a split in the reed. In operation the jacquard raises the yarns of the two filled frames over an inserted pile wire, except at certain predetermined points along the boundary of the design, at which points the jacquard raises the third or unfilled frame causing the pile yarn to remain buried in the back of the fabric. This buried or unraised pile creates a space 10 between the raised tufts 11 of adjacent areas and outlines such design as is desired.

This outline is further accentuated and its resistance increased by staggering the end tufts 12 on each row warp-wise, thus giving protection to those end tufts which form the inset portions of the outline. In its preferred construction these staggered end tufts alternate as they face each other on contiguous design areas.

In constructing a fabric according to my invention the pile warp yarns 3 and 4 are raised throughout the surface of the ground and figure areas, except along the lines 10 which outline the desired design where the pile warp remains buried in the back of the fabric leaving spaces of unraised pile.

It will be seen that my invention of staggered border lines of raised tufts both enhances the appearance of the fabric and overcomes a defect in previous constructions resulting from the tendency of straight border lines of tufts to be flattened in use.

What I claim is:

1. A fabric comprising the combination of stuffer warps, weft shots lying above and below the stuffer warps, binder warps crossing the weft shots above and below and binding the weft shots in place, and a pair of sets of pile warps lying within the body of the fabric with the warps of both sets raised between predetermined adjacent weft shots, and in groups, to provide a pile surface, and unraised between certain other adjacent weft shots to outline a design in said pile surface, the end pile warps along the boundaries of said raised pile groups being raised only every other row weftwise.

2. A fabric comprising the combination of stuffer warps, weft shots lying above and below the stuffer warps, binder warps crossing the weft shots above and below and binding the weft shots

55

in place, and a pair of sets of pile warps lying within the body of the fabric with the warps of both sets raised between predetermined adjacent weft shots, and in groups, to provide a pile surface, and unraised between certain other adjacent weft shots to outline a design in said pile

surface, the end pile warps along the boundaries of said raised pile groups being raised only every other row weftwise, the staggered raised pile tufts alternating as they face each other along adjacent boundaries.

WILLIAM E. CLARKE.
